UNITED STATES PATENT OFFICE.

FREDERICK A. HOYT, OF EAST ORANGE, NEW JERSEY, ASSIGNOR TO THE SIMMS MAGNETO COMPANY, OF EAST ORANGE, NEW JERSEY, A CORPORATION OF NEW JERSEY.

MAGNETO.

1,398,485.

Specification of Letters Patent.

Patented Nov. 29, 1921.

Application filed April 28, 1920. Serial No. 377,168.

To all whom it may concern:

Be it known that I, FREDERICK A. HOYT, a citizen of the United States, residing at East Orange, in the county of Essex and State of New Jersey, have invented certain new and useful Improvements in Magnetos; and I do hereby declare the following to be a full, clear, and exact description of the invention, such as will enable others skilled in the art to which it appertains to make and use the same.

My invention consists in the novel features hereinafter described, reference being had to the accompanying drawings which illustrate one embodiment of the invention selected by me for purposes of illustration, and several modifications thereof, and the said invention is fully disclosed in the following description and claims.

My invention relates more particularly to the manufacture of magnetos for double spark ignition systems, for internal combustion engines, which are constructed to produce from a single secondary coil, two sparks 25 in each cylinder of the engine. In magnetos of this kind, the secondary winding, instead of having one end connected to the primary winding as is customary in ordinary magnetos, is entirely disconnected from the primary winding, and each end of the secondary winding is connected with the ignition circuit. Suitable distributing mechanism connects the secondary winding at the proper times with two spark plugs located in each 35 cylinder of the internal combustion engine. Sparks are produced simultaneously at the spark gaps of both plugs. In the manufacture of such double spark ignition magnetos in which but one secondary winding is employed, it has been found practically impossible heretofore to wind a secondary coil upon the armature of the magneto with sufficient strength of insulation to stand up satisfactorily under long continued use. After 45 a certain amount of use it is found that the insulation of the secondary winding becomes defective and the coil is short-circuited, rendering the magneto inoperative. It has also been found that the insulation is 50 broken through in practically the same portion of the winding in each case, that is to say between layers of the secondary winding, usually near the inner portion of the coil adjacent to the primary winding over

which the secondary winding is wound. If sufficient insulation be placed between the first few layers of the secondary winding to safely withstand the full potential which is built up during the operation of the magneto, it becomes impossible to wind sufficient wire on the armature to give good results, and it has been practically impossible therefore to use this type of magneto in double spark ignition systems. As a result of considerable experiment I have discovered that this serious difficulty in the manufacture of double spark magnetos can be entirely remedied by inserting a suitable condenser in connection with the secondary winding of the magneto armature, and my invention 70 consists broadly in providing such a condenser in connection with the secondary winding of the magneto in a double spark ignition system, and specifically in the particular reorganization of the magneto structure by which the condenser for the secondary winding is incorporated in the magneto, it being understood that it has not been found possible under ordinary circumstances to install such a condenser in or upon the armature itself within the limitations of ordinary magneto construction.

It is my belief and understanding that the difficulty referred to in this type of magneto, which has resulted uniformly in the breaking down of the insulation of the secondary winding, is due to the fact that the high resistance in the ignition circuit, due to the presence therein of the double spark gaps, and the consequent high potential which is built up in the secondary winding, causes a surge of the very steep potential front in the secondary winding, at the instant the primary circuit is broken, which is impressed on the ends of the secondary coil, and results eventually in the generation of a secondary current of such high voltage as to jump the insulation at such points usually adjacent to the inner end portion of the coil, and short circuit the secondary winding, and that the effect of the condenser for the secondary winding, which I term hereafter the secondary condenser, is to cause a charge of opposite polarity to be set up as the potential increases in the secondary winding, and which at the moment of sparking acts to neutralize to a certain extent the current of opposite polarity in the secondary wind-

ing, and thereby decrease the steepness of the potential front, thus protecting the secondary winding against short-circuiting. Regardless of theory, however, and as a practical fact, I have discovered that by the employment of a condenser in conjunction with the secondary winding of a magneto for double spark ignition, the difficulty heretofore experienced is entirely overcome, and the armature may be wound successfully with a normal amount of insulation on the secondary winding, and that the magnetos constructed in accordance with my invention are as efficient and durable for double spark ignition as the ordinary magnetos used for single spark ignition.

In carrying out my invention practically, I may employ a single condenser for the secondary winding, or I may employ two condensers for the secondary winding. Owing to the limitations of magneto structure, I prefer to employ a single condenser for the secondary winding and to locate it between one of the current collectors for the high tension or secondary current, and the distributor, and this construction has been found to be highly practical and efficient.

In the accompanying drawings I have illustrated the preferred manner in which I have contemplated embodying my invention, together with several modifications thereof, which may also be advantageously employed, if desired, to effect the desired results.

Referring to the accompanying drawings, Figure 1 is a vertical sectional view of a magneto for a double spark ignition system, and having embodied therein the preferred form of my invention, in which a single condenser is employed in connection with the secondary winding of the armature and located between one of the current collecting brushes and the distributor, and being a non-rotating structure.

Fig. 1^a is a detail illustrating one means of supporting the dielectric member of the condenser for the secondary winding.

Fig. 2 is a front view of the magneto with the housing of the periodic interrupter removed.

Fig. 3 is a perspective view of the magneto with a portion of the magnets on one side of the same removed for the purpose of showing the condenser for the secondary winding to better advantage.

Fig. 4 is a schematic diagram illustrating the relation of the parts of the magneto.

Fig. 5 is a wiring diagram illustrating the magneto and double spark ignition system.

Fig. 6 is a schematic drawing similar to Fig. 4, illustrating a modified form of condenser, which in this instance may be embodied in the secondary rotor or distributing rotor of the magneto.

Fig. 7 is a view similar to Fig. 6 illustrating a further modification of the condenser embodied in the stationary portion of the distributor.

Fig. 8 is a schematic view similar to Fig. 7 illustrating another arrangement by which two condensers are provided in connection with the secondary winding.

Fig. 9 is a view similar to Fig. 8, also illustrating an arrangement in which two condensers are employed in connection with the secondary winding.

Fig. 10 is a wiring diagram showing the magneto in which two condensers for the secondary winding are employed.

In the preferred embodiment of my invention, which is illustrated in Figs. 1 to 5 inclusive, 1 represents the frame of the magneto, in which is mounted the rotary armature 2 comprising the primary winding, indicated at 3, and the secondary winding, indicated at 4. The secondary winding is ungrounded and is wholly unconnected throughout its length with the primary winding. The primary winding is connected in the usual manner, with a circuit breaker or periodic interrupter indicated at 5, the preferred form of which is shown in Fig. 2, and comprises a rotary part carried by the armature and provided with a fixed contact 6 and movable contact 7 carried by an L-shaped lever 8 having a fiber heel 9, for engaging suitable cams 10—10 for separating the fixed and movable contacts 6 and 7 in a well known way. In the magneto herein shown the armature is wound so as to produce two sparks in each revolution of the same and accordingly two of the cams 10 are provided for this purpose, said cams being mounted on a cam ring 11 so as to be rotatable by means of the timing lever 12 for the purpose of advancing or retarding the spark, in the usual manner. 13 represents the usual condenser arranged in connection with the primary winding and periodic interrupter, in the usual manner. Means are provided for connecting each end of the secondary winding 4 with a high tension current distributing means. In the present instance I have shown two distributors each comprising a circular part, indicated at 14, 15 respectively, and provided with the usual distributing contacts 16, of which six are shown herein, the magneto being arranged for firing a six-cylinder internal combustion engine, and suitable means are provided for connecting each of the contacts of each distributing ring with a spark plug in one of the cylinders, there being therefore two spark plugs in each cylinder, indicated at 17—18 respectively, in the diagram, Fig. 5. In conjunction with the distributor rings I preferably employ the usual distributor rotor, indicated 12

at 19, and provided with two distributing brushes 20, 21 respectively, insulated from each other, this rotor being located above the armature and driven therefrom by means of 5 a pinion 22 on the armature shaft, which engages a gear wheel 23 on the rotor, the gears being arranged to drive the rotor 19 at a speed of one to three, or in other words, three revolutions of the rotor to one 10 of the armature of the magneto. One of the brushes, as the brush 20, is connected with a high tension terminal rod 24 which is concentric with the rotor and is provided at its outer end with a spring actuated 15 brush 25 for engaging a part connected with the high tension current collector 26 provided with a brush 27 for engaging the slip ring 28 on the armature shaft. The slip ring is provided with two segments 29 20 and 30 insulated from each other, and one end of the secondary winding is connected to each of said segments. A second high tension current collector is employed, indicated at 31 provided with a brush 32 for 25 engaging the slip ring on the side opposite from the brush 27 and this current collector is connected preferably by a cable or wire 33 with a brush 34 arranged concentrically with the rotor 19 and engaging a metallic 30 plate 35 connected with the distributor brush 21 so that each end of the secondary winding is connected with a separate distributor. The brush 34 is carried by a cap 37 detachably applied to the exterior of the 35 distributor, in this instance being connected to and supported by the exterior distributor ring 15. 36 represents the usual field magnet of magnets surrounding the armature and united to the magnet frame in the usual, 40 or any preferred manner, and any suitable form or casing or casings may be employed to protect the parts of the magneto from dust and moisture.

In the preferred form of my invention 45 the condenser for the secondary winding is located between one end of the secondary winding and the distributor connected therewith, and preferably surrounds the high tension terminal 24 and its brush 25. In this 50 instance I have shown the condenser as comprising two metallic sleeves separated by a cylindrical body of dielectric material, as glass or mica, and preferably glass. I prefer to form the inner of said sleeves, indicated at 40, integral with a disk 41, against the inner face of which the brush 25 bears, secured to a stem 42, which is screwed into or otherwise secured to the high tension terminal 26. The sleeve 40 and 55 disk 41 forms a cup-shaped metallic member which assists in supporting the dielectric cylindrical body 43, which may be further supported at one end by engagement with the nut 44 on the inner end of the support-

ing bearing for the rotor 19. The cylindrical dielectric body 43 may be protected from breakage due to changes of temperature by interposing rings 45 of rubber or other elastic material between the nut 44 and the dielectric cylinder and between the 65 sleeve 40 and said cylinder, as shown in Fig. 1, for example, or the nut 44 may be provided with a plurality of light spring fingers 46 in some instances, for flexibly holding the inner end of the dielectric sleeve, 70 as indicated in Fig. 1^a, in which the nut is indicated at 44^a, if desired. On the outside of the dielectric cylinder 43 is a metallic sleeve 47 which is conveniently formed as a split sleeve in order to allow for contraction and expansion, as illustrated for example in Fig. 3, the sleeve 47 being located in substantial alinement longitudinally with the inner sleeve 40. Means are provided for connecting the sleeve 47 with the other end 80 of the secondary coil, and in this instance the sleeve 47 is shown as provided with a stud 48 connected by a cable 49 which extends through the dust cap of the machine and is fastened to the lower slip ring brush-holder 90 31. By this arrangement both sides of the secondary winding of the armature are connected to the condenser, one by means of the cable 49, just mentioned, and the other by the stem 42 and the collector brush. The 95 operative effect of this construction will be clearly apparent from an examination of the schematic drawing shown in Fig. 4 (in which the connections from the distributors to the spark plugs are omitted) and the wiring diagram shown in Fig. 5, in which the entire multi-spark ignition system is illustrated. It will be readily seen that the effect of the condenser for the secondary winding is to prevent sparking between coils 100 of the secondary winding no matter how high the potential of the secondary or high tension current may be, and it has been found by practical experience with this apparatus that the use of this condenser in 110 connection with the secondary winding effectively prevents impairment of the insulation of the secondary winding, and permits of the manufacture of magnetos of this character with secondary coils provided with 115 the usual amount of insulation, in which the danger of breakdown by short circuiting of the secondary winding is practically eliminated. It will also be noted that the preferred construction, which I have described, 120 is a very convenient one and permits the installation of the condenser for the secondary current with a minimum of change in the general construction of the magneto.

I wish it to be understood, however, that 125 my invention may also be carried into effect and embodied in other ways, and in Figs. 6 to 10 inclusive, I have illustrated several

additional embodiments of my invention which are entirely practicable and efficient, although I prefer the form illustrated in Figs. 1 to 5 inclusive, and heretofore described.

In Fig. 6 I have represented schematically a slight modification of my invention in which the condenser for the secondary winding is embodied in the rotor of the distributor and comprises two separate metallic plates 140 and 147, between which I preferably arrange a dielectric plate 143 of glass, mica, or other suitable material. The plate 140 is connected with a high tension current distributing means 124 connected with the collector brush 127, the other metallic plate 147 being connected to the brush 134, which is connected by the cable 133 with the other collector brush 132, the other parts represented in Fig. 6 being given the same numerals as the corresponding parts in Fig. 4, with 100 added. In Fig. 6 I have indicated diagrammatically at 117-118 the spark plugs for one of the cylinders of an internal combustion engine. The effect of the condenser shown in Fig. 6 will be identical with that shown in Figs. 1 to 5, in protecting the insulation of the secondary winding and preventing short circuiting between the coils thereof.

In Fig. 7 I have represented, schematically, another slight modification of my invention, in which the condenser for the secondary winding is located upon a stationary portion of the distributor, as for example, the cap 237 which carries the high tension terminal brush 234, connected by the wire or cable 233 with the collecting brush 232. The condenser in this instance comprises a pair of metallic disks 240-247 separated by an intermediate disk 243 of dielectric material. In this instance the disk 240 is connected with the brush 234 and the disk 247 is connected with the other collecting brush 227, in any desired way, as for example by an insulated wire, as indicated at 250. In this figure 224 represents the connection from one of the distributor brushes 220 to the collecting brush 227, and the brush 221 of the distributor will be connected to the terminal brush 234 in the usual manner. I have indicated, in Fig. 7, the spark plugs for one cylinder at 217, 218.

In some instances I may provide two condensers for the secondary winding, and in Fig. 8, for example, I have represented schematically a construction of magneto in which I have combined the form of condenser shown in Figs. 1 to 5, together, with that illustrated in Fig. 7. In this instance the collecting brushes are indicated at 327 and 332, the brush 327 being electrically connected with the inner cylindrical metallic member 340 of the condenser, around which is placed the dielectric cylindrical body 343,

which is in turn surrounded by the cylindrical split metallic member 347, the latter being grounded, as shown at 351, the high tension connection 324 extending from the inner metallic member 340 to the brush 320 of the distributor. In this figure the second condenser is carried by the cap 337 of the distributor and comprises the metallic disk 347^a, the dielectric disk 343^a, and the metallic disk 340^a, the latter being connected to the terminal brush 334 while the disk 347^a is grounded, as indicated at 350, so as to place it in electrical connection with the exterior metallic member 347 of the other condenser, while the disk 340^a is connected by the brush 334 and cable 333 with the collecting brush 332. The second distributor brush 321 is connected to the terminal brush 334 in the usual manner, and the spark plugs for one cylinder are indicated at 317 and 318.

Fig. 9 is a view similar to Fig. 8 and shows an arrangement in which two condensers are employed, one condenser being mounted in the distributor, and in this instance carried on the distributor cap 437 and comprising the metallic plates 447 and 440, separated by the dielectric plate 443, the plate 447 being grounded, as indicated at 450, and the plate 440 being connected with the terminal brush 434, which is connected in the usual manner with the distributor brush 421, the terminal brush 434 being connected as heretofore described by the cable 433 with the collecting brush 432. The other collecting brush 427 is connected by the high tension conductor 424 with the other distributor brush 420, and in connection with the collecting brush 427 I have shown a further modified form of condenser which comprises a pair of metallic plates 440^a and 447^a, separated by a dielectric plate 443^a. In this instance the plate 440^a is connected by a wire 452 with the brush holder for the brush 427, and the plate 447^a is placed in electrical connection with the plate 447 in any suitable manner as by grounding it, as indicated at 451.

Fig. 10 represents a small wiring diagram indicating the arrangement in which two condensers are arranged in conjunction with the secondary winding, the distributors being omitted and the spark plugs for a single cylinder only being indicated, for convenience; the reference characters indicated being the same as those in Fig. 9.

What I claim and desire to secure by Letters Patent is:—

1. In a high tension magneto electric machine, the combination with a field magnet, an armature provided with a primary winding and an ungrounded secondary winding, a periodic interrupter in circuit with the primary winding, and a distributor for the high tension current, of a condenser for the secondary winding comprising a cup shaped

- metallic member, connected to one end of the secondary winding and to said distributor, a cylindrical dielectric member surrounding the said cup shaped member and 65 5 an exterior cylindrical metallic member surrounding said dielectric member, the other end of the secondary winding being connected to said exterior metallic member of the condenser, and to the distributor.
- 10 2. In a high tension magneto electric machine, the combination with a field magnet, an armature provided with a primary winding and an ungrounded secondary winding, a periodic interrupter in circuit 70 15 with the primary winding a distributor for the high tension current, a slip ring on the armature provided with segments each connected to one end of the secondary winding and collecting brushes and 20 25 brush holders therefor, of a condenser for the secondary winding comprising a cup shaped member supported by one of said brush holders and electrically connected to the brush thereof, a cylindrical dielectric member surrounding the cup shaped member, and a cylindrical member surrounding the 30 35 said dielectric member, and electrically connected to the other brush, high tension circuit connections from each brush to the distributor, one of said connections extending into and engaging the inner end of the cup shaped member of said condenser.
3. In a high tension magneto electric machine for multi spark ignition purposes, 40 45 provided with an ungrounded secondary winding, each end of which is connected with the distributor by means of a slip ring, and separate brushes, a condenser for the secondary winding comprising a cup shaped metallic member supported by one of the brush holders, and electrically connected with the brush thereof, a cylindrical dielectric member surrounding said metallic member, and an exterior cylindrical metallic member 50 55 surrounding said dielectric member, the rotary portion of the distributor being provided with a high tension conductor extending into said cup shaped member and provided with a brush engaging the same, and the exterior metallic member being provided with means for connecting it with the other brush holder.
4. In a high tension magneto electric machine for multi spark ignition purposes, 60 65 provided with an ungrounded secondary winding, each end of which is connected with the distributor by means of a slip ring, and separate washer, a condenser for the secondary winding comprising a cup shaped metallic member supported by one of the brush holders, and electrically connected with the brush thereof, a cylindrical dielectric member surrounding said metallic member, and an exterior cylindrical metallic member surrounding said dielectric member, the rotary portion of the distributor being provided with a high tension conductor extending into said cup shaped member and provided with a brush engaging the same, and the exterior metallic member being provided with means for connecting it with the other brush holder, the exterior metallic member of the condenser being split to allow for expansion and contraction, and yielding means interposed between the dielectric member and the metallic surfaces supporting it.

In testimony whereof I affix my signature.

FREDERICK A. HOYT.
